UNITED STATES PATENT OFFICE.

WILLIS D. SHERMAN, OF BROOKLYN, NEW YORK, ASSIGNOR OF THREE-FOURTHS TO CHARLES B. JOHNSON, JOHN J. WILSON, ELLIS H. BAILIE, AND FRANK B. JOHNSON, OF SAME PLACE.

MACHINE FOR MAKING PIPE.

SPECIFICATION forming part of Letters Patent No. 586,569, dated July 20, 1897.

Application filed December 14, 1895. Serial No. 572,126. (No model.)

To all whom it may concern:

Be it known that I, WILLIS D. SHERMAN, a citizen of the United States, and a resident of the city of Brooklyn, Kings county, State of New York, have invented certain new and useful Improvements in Machines for Making Pipe, of which the following is a specification.

My invention relates to machines for manufacturing pipe for sewerage, water-supply, drainage, and other similar purposes. Especially it relates to the manufacture of such pipe whereof the radius of curvature is different at different parts of the pipe, a familiar example being "egg-shaped" pipe.

More particularly the invention consists in the devices for, first, causing the rammers to move in and out according to the changing radius of curvature of the pipe and to reciprocate rapidly in a straight line while thus moving in and out, so as to deliver rapid powerful blows on the cement composition or other material of which the pipe is being made; second, for raising and lowering the core-bar and rammer-head, so that the chains thereof shall be taut and effective at all positions of the core-bar and rammer-head; third, for counterbalancing the rammer-head; fourth, for increasing or decreasing the weight of the rammer-head on the rammers, as desired, for the purpose of varying the force of the blows delivered by the rammers.

Referring to the drawings which accompany the specification to aid the description, Figure 1 is a front and Fig. 2 an end elevation of the machine. Fig. 3 is a plan of the top of the machine; Fig. 4, a broken plan of the cam-plate and rammer mechanism; Fig. 5, a plan of the parts below the core-bar. Fig. 6 is a broken elevation of certain parts arranged so that a pinion on the vertical shaft drives the turn-table and cam-plate without intermediate gears. Fig. 7 is a broken plan view of the same. Figs. 8, 9, and 10 are perspective views, respectively, of the eccentric sliding block and rammer. Fig. 11 is a perspective diagram of the chains for operating the core-bar and rammer-head. Fig. 12 is a sectional detail of the clutch mechanism for controlling the main sprocket-wheel. Fig. 13 is an enlarged plan, partly broken, of the hop-

per, core, mold, and cam-driver. Fig. 14 is a detail section of the hopper; and Fig. 15, a broken section of the core, mold, hopper, and turn-table. Fig. 16 is a section, and Fig. 17 a broken elevation, of the clutch mechanism for connecting and disconnecting the idlers of the core-bar and rammer-head chains. Fig. 18 is a plan, on a very large scale, of the cam-plate and trailers, certain of the rammers being shown in section. Fig. 19 is a plan, and Fig. 20 a broken elevation, of the hold-down-chains of the rammer-head.

Standards A A, Fig. 1, are bolted on the longitudinal raised parts B' of the bed-plate B, B³ being a channel for certain gear-trains. Turn-table C is pivoted on bed-plate B at c, b b being conical antifriction-rollers carried by the bed-plate and on which turn-table C revolves.

C' is the core, doweled into the bottom of mold D. d is a flange on the bottom of mold D, seating in a depression c' in turn-table C. Of course said core, mold, and depression will have the shape in cross-section of the pipe to be formed—for example, egg shape.

E is a hopper suspended by hooks f from core-bar F, which is formed with four arms, as shown, the ends of the arms working in guides in standards A A, f' f', Fig. 1, being rollers under which the flange e' of said hopper E revolves. The flange e of said hopper fits upon the top of mold D. Said core C' is pivoted to core-bar F at f².

G is the rammer-head, working in guides in standards A A.

H is an annular cam-driver provided with gear-teeth on its periphery, revolving on antifriction-rollers i i, Fig. 6, carried by said head G and guided by rollers 1 on said head G, working in the circular groove 2 in the cam-driver H.

I is the annular cam-plate, bolted to the cam-driver H. Of course I could make the cam-plate and cam-driver in one piece, but I prefer to make them separate and bolt them together, as shown.

Main shaft J turns in boxes on standard A A⁵. Main pulley K is loose on shaft J. K' is a friction-disk adapted to bear on the in-

side of pulley K. Links k k connect disk K' with collar K⁸, which slides on and turns with shaft J.

The short arm of lever K², trunnioned at k⁴, is yoke-shaped and carries studs which engage the circumferential groove of collar K⁸. Thus the motion of lever K² in one direction forces disk K' against the surface of pulley K and in the other direction draws said disk K' off said surface.

Bevel-gear j, Fig. 1, on shaft J meshes with bevel-gear l on vertical shaft L. Pinion m on shaft L drives vertical shaft M at the other end of the machine through gear-train 3 4 5 6, carried on studs on bed-plate B. Pinion n of shaft L drives pinion o on shaft p, and pinion q on said shaft p meshes with the gear-teeth on turn-table C. Pinion r on a sleeve s, which turns in boxes carried by rammer-head G, drives pinion 13, also carried by head G, Fig. 1, and pinion 15 on the shaft of pinion 13 meshes with the gear-teeth on cam-driver H. Said sleeve s slides longitudinally on and revolves with shaft L by reason of a feather on said shaft and groove in said sleeve, and said sleeve s is positioned in the said box by collar 20. A similar sleeve S', sliding on shaft M, is carried in boxes on the other end of the rammer-head.

The gearings for driving turn-table C and cam-driver H are arranged so that both turn-table and cam-driver revolve at the same speed in the same direction, and of course turn-table C causes the core C', mold D, and hopper E to revolve at that speed. By changing the gears of the trains different speeds of revolution of the turn-table and cam-plate may be produced suited to different sizes of pipe.

The rammer mechanism.—Rammer-head G is made with annular top and bottom plates 25 26, respectively, connected by tie-rods 28 and posts 30. Frames 31, carrying studs for certain intermediate gears, are also arranged at proper intervals between the plates 25 26, and said frames may have a box for said sleeve S. Slots 32 are formed in said plates 25 26, adjacent to posts 30, for the slides T, and wide radial slots 35, Fig. 4, are cut through said plates in line with the slots 32, approximately normal to the cam-groove 82, 36 being guideways for said slides T. In plan, Fig. 4, said slides are yoke-shaped and have at either side of the post 30 horizontal parallel slides 38 39 at the top and 40 and 41 at the bottom of said yokes. The vertical body part 43, Fig. 6, has a horizontal bush 44 for a reciprocating shaft 45. Projections 50 51 on the inner face of the slides T have caps 52 54, respectively, forming bearings for the rammers, as will be hereinafter described.

A bevel-gear 55, Fig. 4, on sleeve S² meshes with a bevel intermediate gear 56, fixed on short shaft 57, carried on the frame 31 of rammer-head G, and bevel-gear 60 on said shaft 57 meshes at each side with similar gears 61 on similar shafts 45. Each said gear

61 meshes with an intermediate gear 63, similar to the aforesaid gear 55, and each gear 63 in turn meshes with another gear 61 on a shaft 45. On the other side of the machine is a similar series of intermediate gears 55 63, shafts 45, and gears 61. Each said gear 61 has a sleeve 68, Fig. 6, revolving in boxes 70 on said posts 30 and provided with a square axial hole through which reciprocate the square ends of said shafts 45. A round portion 71 of said shafts 45 turns in a bush 44 of slide T, and 72 is an eccentric carried thereby. Shaft 45 is positioned in slide T by a thrust-collar 44. A sleeve 75 turns in the bearing 50 52 of each slide T, being positioned therein by the flange 77 and the collar 78. Said flange 77 carries antifriction-rollers 80 81, (called "trailers,") on studs, as shown, Fig. 9, and said rollers trail in the groove 82 of cam-plate H, said groove 82 being the shape of the pipe to be formed. Thus as cam-plate H revolves said rollers 80 81 will cause slide T, with shaft 45, to reciprocate and sleeve 75 to oscillate according to the varying curvature of cam-groove 82.

Rammers U, one for each shaft 45, are arranged between the core C' and mold D, that part 90 of said rammers which is in the mold 95 being broad and flat, as shown, and conveniently made of a piece of an I-beam, positioned so as to be practically tangential to the core. The upper ends 91 of said rammers are round, being guided through the bearings 52 54 of the slides T, and have way-blocks 93, with horizontal ways 94 95, between which the sliding blocks 92 are retained and reciprocated as the eccentric 72, which works in the hole 92 of said blocks, revolves. The revolution of said eccentric 72 causes the rammers U to reciprocate vertically. The extreme upper ends 96 of said rammers rise into the sleeves 75 and have feathers which work in vertical grooves 99 of the sleeves 75, 110 said sleeves being long enough to permit of the reciprocation of said rammers. Thrust-collars 97 97 position the rammers U in the way-blocks 93. Thus the oscillation of the sleeves 75 causes the flat parts of the said rammers to always take a position tangential to the curvature of the cores C', as before said. Said rammers U may be made in one piece or preferably may have their upper parts separate and connected with the flat 115 lower parts in any suitable manner. Thus the revolution of shafts L M causes the mold, core, and cam-plate to revolve at the same speed in the same direction, the slides T, with the rammers U, to move in and out from 120 the center according to the varying dimensions of the mold, the said rammers to reciprocate so as to deliver rapid powerful blows on and pack the material in the mold around the core, and said rammers to oscillate on 125 their vertical axes, so that the lower parts shall be always practically tangential to the cores C'. This last-named feature is of much importance, for it permits the use of a rec-

tangular-ended rammer having considerable surface in the narrow space between the mold and core and renders the rammers much more effective. Said rammers U may of course be curved in cross-section instead of being rectangular, and in making small pipe the curved form may be preferable.

Mechanism for raising core-bar and rammer-head.—The hub of pulley K carries a pinion 100, meshing with pinion 101, fixed on shaft 102 either with or without an intermediate pinion. Said pinions 100 and 101 have faces broad enough to permit of the reciprocation of shaft 102 without interrupting the meshes of said pinions. Bevel-gears 104 105, with the bevels oppositely and inwardly inclined, are adjacent to each other and loose on shaft 102, being positioned thereon by thrust-collars between the caps 107. Each gear 104 105 has conical flanges 108 109, respectively, on its end. Cones 110 111 are fixed and positioned on shaft 102, so that when said shaft is slid in one direction cone 110 wedges in flange 108 of gear 104, and when slid in the other direction cone 111 wedges in flange 109 of gear 105. Bevel-gear 115, fixed on vertical shaft 116, meshes with both gears 104 105. Worm 117 on shaft 116 meshes with worm-wheel 118, fixed on shaft 120, on which is fixed a sprocket driving-wheel 121, and there is a similar sprocket-wheel 121 on the other end of shaft 120. Thus according to the direction in which shaft 102 is shifted the sprocket-wheel 121 will be revolved in one or the other direction. Said shaft 102 is shifted by bent lever W, trunnioned at 124. Pins on the yoke of the short arm of said lever engage a groove in the periphery of the collars 125, fixed on said shaft 102. A chain X, starting from a becket 126 on one end of core-bar F, passes downward partly around sprocket-wheel 121, thence upward through a hole in the core-bar and partly around an idler 127, loose on shaft 128, which is fixed transversely in standards 129 on top of the machine, thence partly around an idler 131, loose on shaft 132, supported in bearings in standards 133 near the other end of the machine, thence down to a becket 135 at the other end of the core-bar. Therefore chain X has three parallel lengths, respectively, $x^1 x^2 x^3$, and by reason of this arrangement, which is an important part of the invention, said chain X remains taut and will operate the core-bar effectually at all the positions of the same. Sprocket-chain X', similar to chain X, starts from a becket 140 at the end of the core-bar F opposite to becket 126, thence goes downward around idler 141, pivoted on the frame, thence upward through a hole 142 in the core-bar around idler 144, loose on shaft 132, thence around idler 145, loose on shaft 128, thence down to becket 146 on the end of the core-bar near becket 126. Thus chain X' has three lengths $x^4 x^5 x^6$, respectively, parallel to each other and remains taut and effective at all positions of the

core-bar F. There are chains $X^3 X^4$ for the other side of the core-bar, respectively, similar to chains X X' and carried by idlers 150 151, loose on shaft 128, and idlers 153 154, loose on shaft 132. Said four chains operate and keep horizontal the four ends or corners of the core-bar at all its positions. Sprocket-chain Y leads from becket 160 on the top frame A² down and partly around sleeve 161 at one end of head G, thence up and partly around idler 162, loose on shaft 128 and adjacent to idler 127, thence horizontally and partly around idler 165, fixed on shaft 166, turning in bearings on the top of the machine, thence down to a becket 168 on the counterpoise Z. From a becket 169 on counterpoise Z sprocket-chain Y' leads up partly around idler 170, fixed on shaft 166, thence downward partly around idler 172 at the end of head G opposite to idler 161, thence up to a becket 173 on the top frame A². For the other side of head G there are a chain Y², similar to chain Y, and a chain Y³, similar to chain Y', idlers 175 176, fixed on shaft 166, and idler 178, loose on shaft 128. All the hereinbefore-mentioned idlers are sprocket-wheels, and said idlers 162, 165, 170, 175, 176, and 178 are twice the diameter of idlers 127, 145, 150, and 151, because chains Y Y' Y² Y³ each go around an idler that is carried by head G.

Pins 180 181, connected by a cross-bar 183, and which are threaded on their ends, pass through sockets 185 185 in the hub of idler 162 and have heads 188 189, respectively, which enter sockets in idler 127. Springs 193 normally press the heads into said sockets, so that idler 162 revolves with idler 127. A rod 195 leads through a hole in shaft 128, pressing against cross-bar 183, and its other end is engaged by the short end 197 of lever 198, pivoted at 200. 201 is a chamber in shaft 128 to permit the working of lever 198. A rod 205, working in guides 206 207, leads from lever 198 down adjacent to lever W, 210 211 being projections placed on rod 205 to actuate lever W in opposite directions when rod 205 is moved by the head G, striking in its upward and downward motion against lugs 215 216, respectively, on said rod 205. Thus when rod 205 is raised lever 198 takes the position shown in Fig. 16, and pins 180 181 (forming in effect a clutch) enter the holes in idler 127, and idler 162, together with its chain Y, is moved. When rod 205 draws lever 198 down, arm 197 pushes rod 195, the pins are withdrawn from the holes in idler 127, and idler 162 does not move with idler 127. The arrangement of the chains for the core-bar and rammer-head and the clutch, as above described, gives complete control of the movements of the core-bar and rammer-head. The latter is free to rise during the operation of ramming material into the mold without moving the former, or it can be raised by the core-bar or along with it. Thus when the core-bar F is raised by causing sprocket-wheel 121 to revolve in

the proper direction (the clutch at idlers 127 and 162 being normally disconnected when hammer-head is down) said core-bar F lifts rammer-head G with it independently of said clutch mechanism until the rammer-head strikes stop 215. The first upward movement of rod 205 thus produced operates lever 198, so as to permit pins 180 181 to engage idler 127. After this rod 205 travels a little farther until it has thrown lever W to the central position, wherein the bevel-gears 104 105 are both disengaged from shaft 102 and sprocket-wheel 121 stops, also stopping the core-bar.

15 Now to start head G down the operator throws lever W up, thus causing sprocket-wheel 121 to revolve in the proper direction. Pins 180 181 being engaged, as above stated, with idler 127 idler 162 is revolved, operating 20 the chains of the rammer-head and causing it to descend with the core-bar until lug on rod 205 is struck by the rammer-head, first disengaging the clutch at the idlers 127 and 162 and immediately after throwing lever W 25 back to the central position and stopping sprocket-wheel 121. Lever W, it will be seen, also gives the operator a certain direct control of the movements of both core-bar and rammer-head, since by throwing it in the one 30 or the other direction he can raise or depress rod 205 and operate the clutch at the top of the machine by said lever W striking the stops 210 211 on rod 205.

The brake and holddown.—When the counterpoise Z is free to exert its weight on the rammer-head G, evidently the blows of the rammers U will be light. To increase the force of the blows, I have provided, first, a brake mechanism to prevent the counterpoise from 35 acting on the rammer-head, and, second, a holdown to increase the weight of the rammer-head on the rammers; and first describing the brake and its connections wheel 230, fixed on shaft 166, has a strap-brake 234, operated in the usual manner by lever 235, pivoted at 236, Fig. 3. A rod 238, Fig. 1, connects lever 235 with an arm 240 of a bell-crank pivoted at 241. The other arm 242 of said bell-crank is connected by rod 245 with 45 a treadle 250. By depressing the treadle the operator can brake shaft 166 and thus prevent the counterpoise Z from exerting any lifting pull on the head G.

The holdown.—On drums 255, Figs. 19 and 20, fixed on shaft 166, are fastened and wound in the same direction two chains or cables 257 265, respectively. Cable 257 leads down and partly around an idler 259 on shaft 149, and thence up to a becket 260 on one end 50 of rammer-head G. Cable 265 leads from its drum horizontally and partly around idler 269, loose on shaft 128, thence downward and partly around idler 266, loose on shaft 120, and thence up to a becket 270 on head G and 55 diametrically opposite to becket 260. Thus when I use the holdown the brake by stopping the drums 255 causes the cables 257 265

to hold down rammer-head G, thereby increasing the weight of the same on the rammers U.

In Fig. 6 shaft M has pinions n^x and r^x , which mesh, respectively, with turn-table C and cam-driver H without intermediate pinions. In all other respects the arrangement of the parts is the same as hereinafter described.

To change the machine so as to make different sizes of pipe, cam-plate I will be taken off and another plate with a different cam-groove will be substituted, the mold and core being correspondingly changed.

It will be observed that the rammer-head is so constructed that there is at all times a clear opening through the center. This opening is provided in order to permit of feeding the cement from above the rammer-head should I choose to do so.

The operation.—The core-bar and rammer-head being in the position of Fig. 1 a suitable quantity of mixed sand and cement and water is put into the mold and the machine started. From time to time additional material is added, the rammers rising and lifting the rammer-head, because the clutch at the top of the machine is disengaged. When the pipe is finished, the attendant stops the rammers by lever K³, draws down lever W, and thus starts sprocket 121, which moves the core-bar chains and raises the core-bar, which in its turn raises the rammer-head until lever W returns to its middle position in the manner hereinbefore described, stopping the core-bar and rammer-head. Now the mold is removed from underneath the core-bar and another mold substituted. The operator now raises lever W, thus causing the core-bar and rammer-head to descend again to the position of Fig. 1, when lever W is automatically again brought to the middle position. The operator now starts the rammers by lever K³ and makes another pipe. When he wishes to put additional force on the rammers, he depresses treadle 250 and brings the holdown-chains and the brake into operation, as described.

Now, having described my improvements, I claim as my invention—

1. In a pipe-making machine, the combination of a rammer-head a revoluble cam-plate thereon, a shaft and pinion at the periphery of and adapted to drive said cam-plate, rammers, eccentrics or cranks reciprocating said rammers, shafts for the same adapted to be driven by the first-named shaft, and connections between the rammers and the cam-plate so that the revolution of the cam-plate causes the rammers to move in and out from the center of the cam-plate, substantially as described.

2. The combination in a pipe-making machine, of a revoluble cam-plate, oscillating and reciprocating rammers, and trailers on the rammers adapted to engage the cam-plate and oscillate the rammers at right angles to their axis, substantially as described.

3. A rammer-head, rammers carried thereby, slides T adapted to reciprocate in said rammer-head and to move said rammers in and out, ways for the slides, a revoluble cam-plate carried by the rammer-head, trailers on the rammers adapted to engage the cam-plate, and means for rotating the cam-plate, substantially as described.

4. The combination with shafts L M, of a rammer-head, intermediate pinions carried by the rammer-head and certain of said intermediate pinions driven from said shafts L M, driving-pinions meshing with said intermediate pinions, shafts driven by but reciprocating through said driving-pinions, rammers actuated by said last-named shafts, a revolving cam-plate, and connections between said rammers and said plate whereby the revolution of the cam-plate causes the rammers to move in and out, substantially as described.

5. The combination of the annular top plates and bottom plates of a rammer-head, posts between the same, boxes through the posts, gears carried in the boxes, shafts working through and revolving with said gears, slides reciprocating between said top and bottom plates, rammers carried by the slides, a revoluble cam-plate on the rammer-head, and connections between the rammers and the cam-plate, substantially as described.

6. The combination of a core-bar, chains for raising and lowering the same and having three parallel lengths, a sprocket-wheel for driving the chains, and reversing-gear for arresting and reversing the direction of the sprocket-wheel, substantially as described.

7. A rammer-head, chains for raising and lowering said rammer-head, a counterpoise on the end of said chains, sprocket-idlers for said chains, and a brake for arresting at least one of said idlers, substantially as described.

8. The combination of a core-bar, a rammer-head, a chain for said core-bar, a chain for said rammer-head, a driving-sprocket for the core-bar chain, an idler 127 therefor, an

idler 162 for the rammer-head chain adjacent to said idler 127, and a clutch adapted to connect and disconnect said idlers with and from each other, substantially as described.

9. The combination of a rammer-head, hold-down-chains connected therewith and adapted to check the rising of the rammer-head, drums for the chains, and a brake for the drums, substantially as described.

10. The combination of the core-bar, chain therefor, rammer-head, chain therefor, idlers for said chains, a clutch adapted to engage said idlers with and disengage them from each other, and devices adapted to be engaged by the rammer-head for operating the clutch, substantially as described.

11. The combination of the core-bar, chain therefor, sprocket-wheel for driving the chain, rammer-head, chain therefor, idlers for said chains, a clutch for engaging and disengaging said idlers with and from each other, levers for operating said clutches, a rod actuated by said rammer-head and adapted to engage first one and then the other clutch-lever, substantially as described.

12. The combination with a rammer-head adapted to rise and fall above a mold, rammers adapted to work in a mold, and a cam-plate carried by the rammer-head, of an external vertical main shaft adjacent to the rammer-head and adapted to drive the cam-plate and the rammers, substantially as described.

13. A rammer-head provided with a clear central through-and-through opening, substantially as described.

In testimony that I claim the foregoing as my invention I have signed my name, in presence of two witnesses, this 6th day of December, 1895.

WILLIS D. SHERMAN.

Witnesses:

BERNARD J. ISECKE,
HENRY N. BROWN.
